PIPE REAMER

Filed Sept. 20. 1929

FIG. 3

Inventor
H.N. Allinson

By his Attorney
J. Ledermann

UNITED STATES PATENT OFFICE

HERBERT N. ALLINSON, OF SOUTH ORANGE, NEW JERSEY

PIPE REAMER

Application filed September 20, 1929. Serial No. 393,865.

The main object of this invention is to provide a pipe reamer which is fitted securely at the base of the bowl and is self-contained in the pipe.

Another object of the invention is to provide a reamer for pipes; the reamer being secured at the lower end of the bowl when inactive and being adapted to be fed upwardly to remove any carbon or sediment adhering to the surface of the bowl upon manipulation of a feeder stem.

The above and other objects will become apparent in the description below in which characters of reference refer to like-named parts in the drawing.

Referring briefly to the drawing, Figure 1 is a longitudinal, sectional, elevational view of a pipe section showing the reamer applied thereto.

Figure 2 is a top plan view of Figure 1. Figure 3 is a front elevational view of the reamer feed stem.

Figure 4 is a partially sectioned elevational view of a modified type of reamer which may be applied for surfacing the bowl of the pipe.

Referring in detail to the drawing, the numeral 10 indicates the body of a smoking pipe. This body has a suction stem 11 extending radially therefrom. Within the suction stem, 30 a channel 12 is formed which communicates with the bowl 13 in the body of the pipe. The bowl is substantially cylindrical in cross-section and it is the purpose of the reamer fitted to the pipe to scrape the surface of the bowl and remove any sediment therefrom.

A nipple comprising a flange 14 and two threaded sleeves 15 and 16 projects from opposite sides of the flange 14. The externally threaded sleeve 16 enters into the threaded 40 socket of the reamer 17. This threaded socket, indicated by the numeral 18, in the modified form of reamer illustrated in Figure 4, is applied to the construction of both the modified and preferred form of reamer together with a threaded hole 19 which com-

municates with the threaded socket 18 illustrated in Figure 4. The periphery of the preferred type of reamer 17 has cutting teeth 20 applied to its surface—it being noted that the periphery is conical in outline. The sleeve 15 of the nipple is provided with a reduced opening 21 through which the stem 22 of a feeder rod is inserted. This stem 22, at its extremity, is provided with a reduced threaded projection 23 which is adapted to engage the threads 55 in the hole 19 of the reamer. The feeding rod has hinged, foldable wings 24 pivotally secured thereto which wings are adapted to be engaged by the fingers when manipulating the reamer longitudinally in the bowl 13. In 60 the modified form of reamer shown in Figure 4, triangular teeth 25 are formed on the marginal edge of one face. The sleeve 16 is provided with a substantially secured passage-way 26 which serves as a socket for a wrench 65 end when securing the nipple in place in the pipe body.

The preferred type of reamer illustrated in Figure 1 and the modified type illustrated in Figure 4 are identical except for the fact that the preferred form has teeth formed on the peripheral surface while, in the modified form, the teeth are provided on one face. The outlines of these forms are identical and the means of securing the reamer to the sleeve 16 70 and to the feeding rod are the same. When the reamer is not to be used, it sits at the lower base end of the bowl 13 with the threaded socket receiving the end of the stationary sleeve section 16. When it is desired 75 to scrape the surface of the bowl 13, the threaded projection 23 and the stem 22 are inserted into the opening 21 in the sleeve section 15 and slid upwardly until the projection 23 registers in the threaded hole 19. 80 Further rotation of the stem 22 of the feeding rod will rotate the reamer and cause the same to become disengaged from the threads 85 of the sleeve 16 and then the reamer becomes free to perform its function. By slowly 90

feeding the reamer upwardly, the conical teeth 20 or the teeth 25 in the modified form will engage and scrape the surface of the bowl 13 free of any accumulated carbon sediment adhering to its surface. After the scraping operation has been completed the reamer is again lowered by extending the stem 22 out of the guide opening 21 and, after rotation has been completed, the reamer 10 17 finds it is again in engagement with the sleeve 16.

It is to be noted that certain changes in form and construction may be made without departing from the spirit and scope of the 15 invention.

I claim:—

1. In a smoking pipe having a bowl therein, a cutting disk movable in said bowl, a nipple stationary in said pipe, means for 20 attaching said cutting disk to said nipple through rotation of said disk, and means for feeding said disk upwardly in said bowl.

2. In a smoking pipe having a bowl therein, an annular cutting disk, a threaded nipple 25 stationary in said pipe projecting into said bowl, said nipple being adapted to engage said cutting disk when the latter is inactive, and means for detaching said disk from said nipple.

3. In a smoking pipe having a bowl therein, a toothed annular disk movable in said bowl, a stationary nipple in said pipe projecting into said bowl, said cutting disk having a socket therein receiving said nipple 35 when said disk is inactive, an independent means adapted to pass through said nipple and engage said cutting disk for detaching said cutting disk from said nipple and rotate said disk.

4. In a smoking pipe having a bowl therein, a toothed annular disk movable in said bowl and having a threaded hole therein, a stationary nipple in said pipe projecting into said bowl, said cutting disk having a socket 45 therein receiving said nipple when said disk is inactive, and means engaging said threaded hole for detaching said disk from said nipple.

5. In a smoking pipe having a bowl therein, a toothed annular disk movable in said bowl and having a threaded hole therein, a stationary nipple in said pipe projecting into said bowl, said cutting disk having a socket 50 therein receiving said nipple when said disk is inactive, a guide opening in said nipple, an independent slideable means in said guide opening engaging the hole in said disk for detaching said disk from said nipple.

6. In a smoking pipe having a bowl therein, a toothed annular disk movable in said bowl and having a threaded hole therein, a stationary nipple in said pipe projecting into said bowl, said cutting disk having a socket 55 therein receiving said nipple when said disk is inactive, a guide opening in said nipple,

a feeding rod slideable in said opening, a threaded projection on said feeding rod adapted to engage in said threaded hole of said disk, said feeding rod when rotated detaching said disk from said nipple, said rod 70 when urged longitudinally scraping the surface of said bowl with said disk, and means for rotating said rod with the fingers.

In testimony whereof I affix my signature.

HERBERT N. ALLINSON.
